UNITED STATES PATENT OFFICE.

MARIE CLEMENT STAUB, OF WORCESTER, MASSACHUSETTS.

DESIGN FOR A MEDAL OR SIMILAR ARTICLE.

46,376.

Specification for Design.

Patented Sept. 8, 1914.

Application filed June 10, 1914. Serial No. 844,379. Term of patent 14 years.

To all whom it may concern:

Be it known that I, MARIE CLEMENT STAUB, a subject of the Emperor of Germany, residing at Worcester, in the county of Worcester and State of Massachusetts, have invented a new, original, and ornamental Design for Medals or Similar Articles, of which the following is a specification, reference being had to the accompanying drawing.

The figure in the drawing is a view of the obverse side of the medal, showing my design.

I claim—

The ornamental design for a medal or similar article, as shown.

M. CLEMENT STAUB.

Witnesses:

M. O. ROCHAIN,

AYMARD FANZIE.
